His Attorney.

UNITED STATES PATENT OFFICE.

LUDGER E. HUBERT, OF LOWELL, MASSACHUSETTS.

CHAIR AND STOOL.

No. 923,267.

Specification of Letters Patent.

Patented June 1, 1909.

Application filed February 8, 1909. Serial No. 476,595.

To all whom it may concern:

Be it known that I, LUDGER E. HUBERT, a citizen of the United States, residing at Lowell, in the county of Middlesex and 5 Commonwealth of Massachusetts, have invented a certain new and useful Improvement in Chairs and Stools, of which the following is a specification.

This invention relates to chairs and stools 10 provided with either revolving or vertically adjustable seats, or with seats which are both revoluble and adjustable as revolving chairs and piano-stools.

The object of said invention is to secure a 15 lighter, cheaper, stronger and more durable construction and to facilitate repairs if such should be necessary and is accomplished by securing the sleeve-nut which guides the spindle or screw more rigidly in place by 20 means hereinafter described.

Said invention allows the pedestal or pillar commonly used to be dispensed with, thus making the chair or stool much lighter and of less cost than heretofore, prevents 25 wobbling of the seat and the loosening of the sleeve-nut, and facilitates the removal of said sleeve-nut in case of breakage and, of course, lessens the cost of setting up and knocking down for purposes of transporta- 30 tion.

In the accompanying drawing, Figure 1 is a vertical central section of the seat of a revolving and vertically adjustable chair or stool and the parts which constitute my invention; Fig. 2 is a horizontal cross-section on the line 2 2 in Fig. 1; Fig. 3 is a front elevation of the sleeve-nut and a vertical section of the adjacent parts; Fig. 4, a front elevation of a revolving and vertically ad- 40 justable stool provided with my improvement, omitting one of the legs.

The seat A has secured to its under side a plate B by means of screws b, said plate having a central hub b¹ provided with a 45 central opening b² which tapers upwardly to receive and fit the tapering upper end c of the externally screw-threaded spindle C;—these parts being of the usual construction.

50 The sleeve-nut D is internally screw-threaded at d⁵ to engage the screw-threaded spindle, substantially as heretofore used. Externally said sleeve-nut D is provided at its upper end with a flange d which rests 55 upon the "top" E and below said flange is provided with a relatively coarse external

screw-thread d¹ which is notched, as at d², preferably, at least once in every turn of the screw, to cut an internal screw-thread in said top E for its reception, the hole e for 60 the reception of said sleeve-nut being of the same diameter as the external root-diameter of said sleeve-nut or just large enough to admit the barrel of said sleeve-nut.

Below the top E, the sleeve-nut D is reduced at d³ to pass through a washer F but is provided on said reduced part d³ with a projection or spline d⁴ which fits a corresponding key-seat or groove f which extends radially from the eye of said washer 70 and prevents said sleeve-nut and washer from turning in or on each other. The washer F is provided with upwardly projecting points or prongs f¹ which enter the underside of the top E and prevent the 75 washer and the sleeve-nut D from turning on said top E.

The reduced part d³ of the sleeve-nut D below the spline d⁴ is provided with another externally screw-thread d⁵ (finer than 80 the thread d¹), on which is turned an internally threaded holding-nut G up against the washer F forcing the prongs f¹ into the underside of the top and to retain said prongs in said top. 85

When the washer F is in place, its prongs prevent the turning of said washer and the washer with its seat engaging the spline d⁴ prevents the turning of the sleeve-nut D in the top E. 90

The holding-nut G is represented as provided with notches g to engage a spanner or wrench for turning said nut.

The top E is supported by legs H represented as united by braces I in an obvious 95 manner.

The flange d, the washer F and the holding nut G prevent any vertical movement of the sleeve-nut D in the top E and with the coarse screw-thread d¹ make any movement of said sleeve-nut in said top impossible without loosening said holding nut. 100

If necessary for any reason, the sleeve-nut D may be unscrewed from the top E after removing the holding nut G and 105 washer F.

By omitting the internal screw-thread of the sleeve-nut and the thread of the screw-spindle, this invention may be applied to chairs and stools, the seats of which are 110 capable of turning without vertical movement.

I claim as my invention:—

1. The combination in a chair or stool, of a sleeve adapted to pass through a top and to receive a spindle and having an external screw-thread and below said thread having a reduced part provided with a spline or projection, a washer having a key-seat to receive said spline and provided with prongs to enter the under side of said top, 5 and a nut engaging another screw-thread, with which said reduced part is provided below said spline.

2. The combination in a chair or stool, of a sleeve adapted to pass through a top 15 and having at its upper end an external flange to rest on said top and having an external screw-thread and having below said thread a reduced part provided with a spline, a washer having a key-seat to receive said spline and provided with prongs 20

to enter the under side of said top, and a nut engaging another screw-thread, with which said reduced part is provided below said spline.

3. The combination in a chair or stool, of a sleeve adapted to pass through a top and having an external screw-thread notched to form cutting edges and below said thread, having a reduced part provided with a spline, a washer having a key-seat to receive said spline and provided with prongs to enter the under side of said top, and a nut engaging another screw-thread with which said reduced part is provided. 25 30

In witness whereof, I have affixed my signature in presence of two witnesses. 35

LUDGER E. HUBERT.
